UNITED STATES PATENT OFFICE

125,969

DESIGN FOR A DRESS

Charles Lang, New York, N. Y.

Application January 15, 1941, Serial No. 98,054

Term of patent 3½ years

To all whom it may concern:

Be it known that I, Charles Lang, a citizen of the United States, residing in New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

CHARLES LANG.
